UNITED STATES PATENT OFFICE

JOHANN POBUTA, OF ELIZABETH, NEW JERSEY.

AIR-CRAFT.

1,075,791.

Specification of Letters Patent. Patented Oct. 14, 1913.

Application filed November 11, 1912. Serial No. 730,701.

To all whom it may concern:

Be it known that I, JOHANN POBUTA, a subject of the Emperor of Austria-Hungary, residing at Elizabeth, in the county of Union and State of New Jersey, have invented certain new and useful Improvements in Air-Craft, of which the following is a specification, reference being had therein to the accompanying drawing.

10 This invention relates to an air craft, and the primary object of my invention is to provide an air craft constructed upon the principle of an aeroplane, said craft having a semi-cigar shaped body that coöperates with planes in sustaining the craft in the air.

Another object of this invention is to provide an air craft with novel propeller and steering plane that coöperate with a rudder. 20 in safely guiding the air craft when a flight.

A further object of this invention is to provide an air craft that has a large passenger capacity and ample space for the necessary crew and operating mechanism of the air craft. 25

A still further object of this invention is to provide an air craft that is simple in construction, easy to manipulate and highly efficient for various kinds of service.

30 With the above and other objects in view, the invention resides in a novel construction, combination and arrangement of parts to be hereinafter specifically described and then claimed.

35 Reference will now be had to the drawings, wherein:

Figure 1 is a perspective view of the air craft. Fig. 2 is a longitudinal sectional view of the same, and Fig. 3 is a plan of a portion of the air craft. 40

Further describing my invention with reference to the drawings wherein like numerals denote corresponding parts throughout: 1 denotes a platform that is cigar shaped in plan and the forward and rear ends of said platform are provided with heads 2 and 3, said heads being connected by longitudinal bulging equally spaced ribs 4 that coöperate with said platform in forming a frame work that is covered by strong and durable thin metallic plate, canvas or other suitable material to form a hollow craft body that is semi-cigar shaped. 45

50 6 denotes a deck house or cabin located upon the platform 1 and retained thereon

by straps 7 that extend under the body of the air craft. The deck house or cabin is for passengers and to safely guard the passengers upon the platform 1, said platform has a railing 8 that also extends around 60 lateral extensions 9 of said platform, these lateral extensions serving as a bridge or station from which observations can be made.

10 and 11 denote parallel main sustaining planes that are arranged transversely of 65 the air craft above the cabin 6. The plane 10 is connected to the walls of the cabin by angle brackets 12 and to the straps 7 by angularly disposed tie rods 13, the tie rods 13 extending to the ends of the plane 70 and to points intermediate the ends of said plane, whereby the plane will be firmly held against warping and deflection when strong air currents are encountered. The plane 11 is spaced apart and above the 75 plane 10 by vertical supports 14. The ends of the plane 11 are bent downwardly in proximity to the ends of the plane 10 and connected to said plane by supports 15.

16 denotes tiltable planes trunnioned between the endmost support 15, said planes being cut away, as at 17 to provide clearance for the intermediate supports 15. 80

18 denotes longitudinal partitions carried by the central supports 14, said partitions 85 forming a compartment for a cylindrical reservoir 19 that is suspended from the plane 11 by straps 20.

21 denotes longitudinal bearings carried by the rear edge of the plane 10, intermediate the ends of said plane and the cabin 6. Journaled in the bearings 21 are propeller shafts 22 having two-blade propellers 23. The forward ends of the shafts 22 are provided with belt wheels 24 and passing over 90 said wheels are belts 25 that extend over belt wheels 26 journaled in bearings 27, carried by the roof of the cabin 6. 95

28 denotes a floor located in the hollow semi-cigar shaped body of the air craft, said floor supporting an engine or motor 29 that represents a suitable source of power for operating the air craft, said engine or motor receiving fuel or current from the reservoir 19. 100

30 denotes a driven shaft of the engine or motor and one end of this shaft has a belt wheel 31 over which passes a belt 32 that extends to the belt wheels 26 of the bearings 27, said belt extending through the cabin 6. 105

- The belt wheels and belt simply represent one form of transmission that can be resorted to for driving the propeller shafts 22. 33 denotes a beveled gear wheel carried by the opposite end of the driven shaft 30 and this beveled gear wheel meshes with a similar wheel 34 mounted upon a shaft journaled in a bearing 35, carried by the top of the engine or motor 29. The same shaft is provided with a beveled gear wheel 36 meshing with a similar wheel 37 mounted upon the inner end of a propeller shaft 38 that is journaled in the bearing 35 and the head 3 of the air craft. The outer or forward end of the propeller shaft 38 has a two-blade propeller 39, similar to the propellers 23. 40 denotes a hatch-way in the platform or deck 1 of the air craft and 41 a stairway leading from the hatch-way to the floor 28. 42 denotes bearings located upon the platform or deck 1 at the forward and rear ends thereof and these bearings support tilttable and adjustable curved planes 43 and 44. 45 denotes a stationary fin carried by the underside of the craft body and the rear end of this fin and the head 2 support an adjustable rudder 46 that is provided with side straps 47 connected by tie rods 48 to the cranks 49 of a transverse shaft 50. The shaft 50 is journaled transversely of the craft body and said shaft has cranks 51 within the body that are connected to rods 52 extending in proximity to the engine or motor 29, whereby an operator upon the floor 28 can easily control the movement of the adjustable rudder 46. 53 denotes hangers carried by the craft body and these hangers support a four wheel truck 54. 55 denotes a revoluble shaft journaled in the body of the air craft and having the ends thereof protruding from the sides of the body. Mounted upon the ends of the shaft 55 are three-bladed wheels 56, each blade of the wheels having inclined slats 57. The shaft 55 is driven by the engine or motor 29 and these side wheels are adapted to coöperate with the propellers 23 and 39 in moving the air craft through the air. 58 denotes a ladder carried by the air craft whereby the crew and passengers can easily ascend to the platform or deck 1 of the air craft. In operation, the planes 16, 43 and 44 can be operated from a suitable station and the operation of the propellers and side wheels, also the movable rudder 46, controlled from within the body of the air craft.
- What I claim is:—
1. An air craft comprising a semi-cigar shaped hollow body having its top formed with a flat platform, a deck house mounted upon said platform, straps extending around said body and secured to the deck house for maintaining the latter in position, parallel

main sustaining planes arranged transversely of said body and with the lowermost plane mounted upon said deck house, means for securing said lowermost plane to said deck house, tie rods for securing said lowermost plane to said straps, a pair of rearwardly projecting propellers carried by said lowermost plane, means for driving said propellers, a fin projecting from said body at the rear thereof, a rudder connected to the stern of the body, and a propeller at the bow of the body and driven from the means for operating the other propellers.

2. An air craft comprising a semi-cigar shaped hollow body having its top formed with a flat platform, a deck house mounted upon said platform, straps extending around said body and secured to the deck house for maintaining the latter in position, parallel main sustaining planes arranged transversely of said body and with the lowermost plane mounted upon said deck house, means for securing said lowermost plane to said deck house, tie rods for securing said lowermost plane to said straps, a pair of rearwardly projecting propellers carried by said lowermost plane, means for driving said propeller, a fin projecting from said body at the rear thereof, a rudder connected to the stern of the body, a propeller at the bow of the body and driven from the means for operating the other propellers, and bladed wheels carried at the sides of said body below said deck house and driven from the means for operating the propellers.

3. An air craft comprising a semi-cigar shaped hollow body having its top formed with a flat platform, a deck house mounted upon said platform, straps extending around said body and secured to the deck house for maintaining the latter in position, parallel main sustaining planes arranged transversely of said body and with the lowermost plane mounted upon said deck house, means for securing said lowermost plane to said deck house, tie rods for securing said lowermost plane to said straps, a pair of rearwardly projecting propellers carried by said lowermost plane, means for driving said propellers, a fin projecting from said body at the rear thereof, a rudder connected to the stern of the body, a propeller at the bow of the body and driven from the means for operating the other propellers, a vertically disposed bearing located upon said platform in proximity to the bow and stern of said body, and a tilttable curved plane carried by each of said bearings.

4. An air craft comprising a semi-cigar shaped hollow body having its top formed with a flat platform, a deck house mounted upon said platform, straps extending around said body and secured to the deck house for maintaining the latter in position, parallel main sustaining planes arranged trans-

versely of said body and with the lowermost plane mounted upon said deck house, means for securing said lowermost plane to said deck house, tie rods for securing said lowermost plane to said straps, a pair of rearwardly projecting propellers carried by said lowermost plane, means for driving said propellers, a fin projecting from said body at the rear thereof, a rudder connected to the stern of the body, a propeller at the bow of the body and driven from the means for operating the other propellers, depending longitudinal partitions carried by the upper of said planes, and a reservoir suspended from the upper plane and arranged between said partitions.

5. An air craft comprising a semi-cigar shaped hollow body having its top formed with a flat platform, a deck house mounted upon said platform, straps extending around said body and secured to the deck house for maintaining the latter in position, parallel

main sustaining planes arranged transversely of said body and with the lowermost plane mounted upon said deck house, means 25 for securing said lowermost plane to said deck house, tie rods for securing said lowermost plane to said straps, a pair of rearwardly projecting propellers carried by said lowermost plane, means for driving said propellers, a fin projecting from said body at the rear thereof, a rudder connected to the stern of the body, a propeller at the bow of the body and driven from the means for operating the other propellers, and tilttable 30 planes interposed between the ends of the main planes. 1

In testimony whereof I affix my signature in the presence of two witnesses.

JOHANN POBUTA.
